(57) **CLAIM**

The ornamental design for a notebook card holder, as shown and described.

DESCRIPTION

FIG. 1 is a perspective view of a notebook card holder according to the present invention;

FIG. 2 is a front elevation view of the notebook card holder of FIG. 1;

FIG. 3 is a rear elevation view of the notebook card holder of FIG. 1;

FIG. 4 is a right elevation view of the notebook card holder of FIG. 1, the left elevation being a mirror image thereof;

FIG. 5 is a top plan view of the notebook card holder of FIG. 1;

FIG. 6 is a bottom plan view of the notebook card holder of FIG. 1;

FIG. 7 is a front elevation view of the notebook card holder of FIG. 1 shown in a closed position;

FIG. 8 is a rear elevation view of the notebook card holder of FIG. 7;

FIG. 9 is a right elevation view of the notebook card holder of FIG. 7, the left elevation being a mirror image thereof;

FIG. 10 is a top plan view of the notebook card holder of FIG. 7; and,

FIG. 11 is a bottom plan view of the notebook card holder of FIG. 7.

The broken lines in the figures illustrate unclaimed environment only and form no part of the claimed design.
